EJECTOR FORK

Seymour Livingston, New York, N. Y.

Application November 30, 1944, Serial No. 565,859

4 Claims. (Cl. 30—129)

1

The invention relates to new and useful improvements in forks.

More specifically, the present invention relates to a fork for use in eating or carving and characterized by having an ejector for pushing the material lifted by the fork off of the tines.

Still another object of the invention is to provide a fork as aforesaid in which the ejector is adapted to be actuated manually for ejecting and to be returned to retracted position by a spring.

A further object is to provide a fork as aforesaid having means for holding the ejector in different positions to which it has been manually moved.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a fork constructed in accordance with this invention.

Fig. 2 is a central longitudinal section through the fork, parts being shown in full.

Fig. 3 is a similar view to Fig. 2 but, with a part, elevationally shown in Fig. 2, here shown in axial section.

Fig. 4 is an enlarged section on the line 4—4 of Fig. 3.

Fig. 5 is an enlarged perspective view of a latch elevationally shown in Fig. 3.

The present invention is directed toward providing a fork which can be employed in serving and which is provided with an ejector for pushing food off of the tines of the fork.

The fork 10, according to this invention comprises a hollow body 11 which serves as a handle for the person using the fork. A coil spring 12 is housed in the hollow interior of the body, resting at its bottom. A plunger 14 is disposed within the coil spring and extends at its opposite ends beyond opposite ends of the body. A pin 15 passing through the plunger in the hollow body at the top of the spring, forms an abutment for the top end of the spring.

A plate 16 is formed as an integral unit at the bottom of the hollow body. This plate has a central orifice through which the plunger extends, and on either side thereof a tine 17 is formed integral with the plate 16. While only two tines are shown, a greater number may be employed if desired. The tines are sharp but if desired, they may be dull.

A plate 18 is formed as an integral member at the bottom with the plunger 14. This plate has two spaced longitudinal orifices through which pass the tines 17. At the top of the plunger

2

is a knob 19 which may be secured to the plunger by means of an internal thread matching an external thread on the upper end of the plunger.

The body is provided with a flange 20 extending into its hollow interior at the top thereof, forming an abutment for the pin 15, spring 12 normally pressing pin 15 against this flange 20 and thereby holding plate 18 adjacent plate 16.

The plate 18 forms an ejector for the tines, the plunger being the means for manually moving the ejector to eject food from the tines and the spring 12 being the means for returning the ejector to normal position when the plunger is released. Body 11 is shown made of two parts 11^a and 11^b threadedly connected together. While making the body in two parts facilitates assemblage of the various parts of the fork, the body may be made in one part if desired.

The operation of the fork, as so far described, is as follows:

The fork, as aforesaid, may be employed in serving food, carving meat or the like, or for other purposes for which an ordinary household fork is employed. The person using the fork sticks the tines of the fork in or under the material to be lifted, and then pushes against the knob 19, the plate 18 sliding along the tines and pushing the food into the plate bowl or platter, the orifices of the plate 18 wiping the tines clean. The person then releases the knob and the spring 12, pressing against pin 15, returns the plate 18 to its original position adjacent the plate 16.

As shown in Fig. 4, the plunger 14 is hollow. The body part 11^b has two annular notches 21 and 22, each of which has a horizontal top face and an inclined bottom face. A spring latch 23 is disposed in the hollow interior of the plunger above the top of the body and is pivoted therein by a pin 24. The latch has a latch member 25 projecting through a port 26 in the plunger wall and thereabove an arm 27 projecting through a port 28 in the plunger wall above port 26. The latch terminates at its upper end in an integral plate spring 29. This spring 29 has its upper end disposed in an annular groove 30 formed in the upper end of the plunger around a stem portion 18' centrally depending from the underside of the part of the knob overlying its internally threaded bottom skirt. A ring 31 is slidably mounted on the plunger above the arm 27.

The person using the fork may move the ring 31 over the arm 27 so that the latch member 25 is pushed into the interior of the plunger in an out of the way inoperative position. At times it may be desirable to use the fork with the ejector plate 18 at an intermediate position on the tines. For instance this may be desirable when a child is using the fork or when the fork

is being used to pick up something it is not desired to entirely pierce, as when the fork is being used to hold a steak for carving and it is not desired that the tines should stick through the steak and press against the plate therebeneath. The advantage of this in the case of metal plates, such as silver, is obvious.

When it is desired to so shorten the effective length of the tines, the ring 31 is slid above the arm 27 and the plunger is pushed downward until the latch member 25 fits in either the groove 21 or 22 depending on the effective length of the tines desired. To return the plate 18 to normal position, all that is necessary is to push against the arm 27, thereby releasing the latch member 25 from the groove 21 or 22 as the case may be, spring 12 then pushing the plunger upward.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. An ejector fork comprising a body having a central bore, a plate secured to one end of said body having an orifice in line with said bore, a hollow plunger disposed in said bore and extending beyond said body and plate at its opposite ends, tines secured to said plate and extending away from said body, an ejector plate having orifices through which said tines extend secured to the adjacent end of said plunger, a coil spring in said bore urging said plunger in a direction holding said plates together, and means for holding said ejector plate at a position spaced from said body plate against the resistance of said spring.

2. An ejector fork comprising a body having a central bore, a plate secured to one end of said body having an orifice in line with said bore, a hollow plunger disposed in said bore and extending beyond said body and plate at its opposite ends, tines secured to said plate and extending away from said body, an ejector plate having orifices through which said tines extend secured to the adjacent end of said plunger, a coil spring in said bore urging said plunger in a direction holding said plates together, and means for holding said ejector plate at a position spaced from said body plate against the resistance of said spring, said means including a latch pivoted in said hollow plunger adapted to coact with the wall of said body bore.

3. An ejector fork comprising a body having a central bore, a plate secured to one end of said body having an orifice in line with said bore, a hollow plunger disposed in said bore, and extending beyond said body and plate at its opposite ends, tines secured to said plate and extending away from said body, an ejector plate having orifices through which said tines extend secured to the adjacent end of said plunger, a coil spring in said bore urging said plunger in a direction holding said plates together, and means for holding said ejector plate at a position spaced from said body plate against the resistance of said spring, said means including a latch pivotally mounted in said plunger bore and having a latch member extending through an orifice in the wall of said plunger, a groove in said body bore for coaction with said latch member, and spring means urging said latch member through said orifice.

4. An ejector fork comprising a body having a central bore, a plate secured to one end of said body having an orifice in line with said bore, a hollow plunger disposed in said bore and extending beyond said body and plate at its opposite ends, tines secured to said plate and extending away from said body, an ejector plate having orifices through which said tines extend secured to the adjacent end of said plunger, a coil spring in said bore urging said plunger in a direction holding said plates together, and means for holding said ejector plate at a position spaced from said body plate against the resistance of said spring, said means including a knob on the other end of said plunger having an annular internal groove disposed over the adjacent end of said plunger bore, a latch pivoted in said plunger bore having an integral plate spring part disposed in said knob groove, a latch member extending through an orifice in the wall of said plunger and a latch-operating knob extending through an orifice in said plunger wall, said body bore having a groove adapted to coact with said latch member.
